UNITED STATES PATENT OFFICE.

ALBERT SANFORD, OF GOLDEN CITY, MISSOURI, ASSIGNOR OF ONE-HALF OF HIS RIGHT TO J. W. HICKS, OF SAME PLACE.

MECHANISM FOR PROPELLING CARS.

SPECIFICATION forming part of Letters Patent No. 232,652, dated September 28, 1880.

Application filed June 23, 1880. (Model.)

To all whom it may concern:

Be it known that I, ALBERT SANFORD, of Golden City, in the county of Barton and State of Missouri, have invented certain new and useful Improvements in Mechanism for Propelling Cars; and I do hereby declare the following to be a full, clear, and exact description of the invention, such as will enable others skilled in the art to which it pertains to make and use it, reference being had to the accompanying drawings, which form part of this specification.

My invention relates to an improved mechanism for propelling cars and vehicles; and it consists in the combination and arrangement of wheels and levers, whereby a man, by turning a crank, can propel a car or vehicle smoothly and rapidly along, as will be more fully described hereinafter.

The object of my invention is to provide a cheap and simple mechanism, which can be applied to street-cars and other such vehicles, whereby a man can propel a car and thus dispense with all need of horses or other animals to draw it.

Figure 1 is a side elevation of my invention. Fig. 2 is an inverted view of the same.

A represents the frame of a car which has secured to it, at one end, a supporting-frame or standard, B. Journaled in the upper end of this standard is a shaft, C, which is provided with a crank, D, on its inner end, and a gear-wheel, E, upon its center. This gear-wheel meshes with the pinion F on the shaft G, which shaft is also journaled in the upper part of the supporting-frame; and has a driving-wheel, O, and a balance-wheel, H, secured to its outer end. Passing down from the pulley O, around a pulley, I, on the end of the shaft J, which extends across the under side of the car, is a driving-belt, L, which communicates the power from the shaft G to the shaft J.

The balance-wheel is provided with a wrist-pin, and fastened to this wrist-pin is the connecting-rod N, which has its opposite end piv-

oted to the upper end of the lever P, which is pivoted on one side of the frame A. The lower end of this lever P has pivoted to it a connecting-rod, Q, which extends toward the shaft J and has its inner end pivoted to the lever R, which is pivoted on the under side of the frame A. This lever R has pivoted to its shorter end, on the opposite side of the car from the mechanism above described, a connecting-rod, S, which rod has its outer end fastened to a crank, T, on the opposite end of the shaft J from the driving-pulley. This shaft J has a pinion, U, and this pinion meshes with a large gear-wheel, V, on the axle W of one of the pairs of driving-wheels upon which the frame A is placed.

It will be seen that power is applied to both ends of this shaft J for the purpose of applying a much greater power to it than could be done to one end alone, and so as to impart a much more steady and even motion to it. By using a driving-belt which runs from the shaft G, and then operating the levers by the balance-wheel, a man is able to propel a car or any other similar vehicle along at a rapid and even rate, and thus dispense with all need of animals to draw the vehicle or car.

Having thus described my invention, I can claim—

The combination of a driving-shaft, G, a belt, L, and a shaft, J, with a balance-wheel and lever that are pivoted upon the side of the car, and a lever that is pivoted on the under side of the car, and their connecting-rods, whereby the power is applied to the end of the shaft J from two different sources, substantially as set forth.

In testimony that I claim the foregoing I have hereunto set my hand this 18th day of June, 1880.

ALBERT SANFORD.
